UNITED STATES PATENT OFFICE.

THEODORE F. VANDEGRIFT, OF NOAH, INDIANA.

FENCE-MACHINE.

SPECIFICATION forming part of Letters Patent No. 341,706, dated May 11, 1886,

Application filed December 18, 1885. Serial No. 186,036. (Model.)

To all whom it may concern:

Be it known that I, THEODORE F. VANDEGRIFT, a citizen of the United States, residing at Noah, in the county of Shelby, State of Indiana, have invented certain new and useful Improvements in Fence-Machines, of which the following is a specification, reference being had therein to the accompanying drawings.

This invention relates to machines for twisting wires so as to hold slats in position in the manufacture of combined wire and slat fences, the object of my improvement being to provide a means whereby a series of parallel and horizontal wires may be twisted alternately in opposite directions, so as to bind between said wires the vertical slats, so as to hold said slats securely in position.

My invention consists in the construction and combination of the parts, as will be hereininafter fully set forth, and specifically pointed out in the claims.

My invention also consists in combining with the twisting device gages, which are carried thereby, for holding and adjusting the vertical slats in position prior to being secured in place by the twisting of the wires.

My invention also consists in the improved means for twisting the wires about the slats by a semicircular rotary motion, as will be hereininafter fully set forth.

In the accompanying drawings, which illustrate my invention, Figure 1 is a perspective view of a fence-making machine constructed in accordance with my improvement. Fig. 2 is an end view. Fig. 3 is a side view, and Figs. 4, 5, and 6 are detail perspective views.

In the accompanying drawings, A refers to the post or upright, which is secured firmly in the ground, and to this post are secured at equal distances from each other a series of horizontal wires, *a a a*, said wires being arranged in pairs, said wires being indicated by the letters *a'* and *a''*. The vertical slats which are held in place between the twists or turns in the wires are represented by the letters *A'*.

B refers to a frame, which is secured in the ground at a suitable distance from the post A, beyond the end of the fence, said frame consisting of beams between which pass shafts *b* and *b'*, the shaft *b'* being provided with a crank-

handle for rotating the same. The upper shaft has on one end a windlass, around which a rope passes, which is connected to the end of the shaft *b'*, for applying power to the small shaft. Around the central portion of the small shaft a flexible connection passes, to the end of which is secured a hook, *b''*, which engages with the perforated plate *c*, which is attached to the central portion of the vertical bars *C C*, to which the ends of the wires *a'* and *a''* are attached. By means of the windlass hereinbefore described the wires are kept taut, and they may be tightened or slackened, as desired.

The supporting-bars of the windlass have attached thereto blocks *B'*, between which the shafts *b* and *b'* pass, and the rotation of said shafts is prevented by frictional contact of the blocks upon the shafts, bolts being provided for properly adjusting the contact.

D refers to a suitably-constructed rectangular frame, which consists of vertical side pieces, *D'*, which are connected to each other by transverse end pieces, *D''*, thus forming a rigid rectangular frame. One of the vertical pieces *D'* has secured thereto a handle, *d*, and opposite thereto is pivotally attached an S-shaped link, *E*, as will be hereininafter fully set forth.

The upright *D'*, opposite the one having attached thereto a handle, *d*, is provided at suitable intervals with bars *F*, which project inwardly therefrom, said bars at their outer ends being T-ended and perforated, so as to provide a means for rigidly connecting them to the upright *D'*, while the inner end is enlarged and provided with segmental slot *f*, as is fully shown in Fig. 6 of the accompanying drawings.

G refers to a bar, which is provided centrally with a member, *G'*, which projects at right angles therewith, said member carrying at its end a cross-head, *g*, the ends of which are slotted or recessed, as shown at *g'*, and on a line with these recesses *g'* the bars *G* are provided with slots *h h*. The ends of the bars *G* are provided with outwardly-projecting bolts *h' h''*, which are of different lengths, the bolt *h'* being adapted to be passed through the segmental slot *f* in the arm *F*, so as to provide

a pivotal connecting means between said arm and bar, while the opposite bolt, *h*'' passes through a perforation, *i*, in the end of the arm *I*, which is rigidly connected to the vertical bar *J*, which is pivotally connected by means of the S-shaped link *E* to the vertical side pieces, *D*', of the frame *D*. The vertical bar *J* has secured thereto, by means of bars *j* and *j*', a handle, *k*, the position of which may be varied by reversing the position of said attaching-bars.

The bar *G* has pivoted thereto on the same side as the projecting member *G*' a bent latch, *H*, which is adapted to partially cover the key-hole slots *h*, and the end of this latch is bifurcated, so as to engage and be held in place by a projecting pin, *i*''', which engages therewith.

L refers to a gage-plate, which is adjustably attached, by means of a set-screw, *l*, to the projecting member *G*', and said gage-plate is adapted to abut against the edge of the vertical slat, so as to regulate the distance between the same.

25 In building a fence with my improved wire-twisting machine the operation is as follows: The horizontal wires *a*' and *a*'' are first passed through the slots *g*' in the cross-head *g*, and also through the slots *h* in the bars *G*, where 30 they are retained by the latches *H*. The ends of the wires are then secured to the vertical bars *C* *C*, and by means of the windlass attached to the frame *B* the wires are tightened. The frame *D*, which carries the twisting mechanism, is now supported so as to be 35 movable longitudinally on the wires, the lower cross-bar, *D*'', preferably resting upon the ground. When a slat has been passed between the wires, the frame *D* is moved toward 40 said slat until the gage-plates *L* abut against the edge of said slat. The handles *d* and *k* are then grasped by the operator, and the handle *k* is moved either upwardly or downwardly, according to the position of the bolt 45 *h*'', which may be either above or below the bar *I*, so as to cause the bar *G* to have almost a complete rotation, which will cause the wires between the slats to be twisted, each wire having a half-turn upon the other. This 50 twisting movement will cause the wires to be unlocked and partially embedded in the slats, so as to hold said slats securely in position. After one slat has been secured in position the frame *D* is moved along the wires and the 55 same operation repeated, the movement of the bar *J* and the twisters being in an opposite direction. By thus organizing the parts the wires at the rear end of the apparatus or near the windlass are not twisted, but are kept 60 uniformly nearly parallel with each other.

It will be noted that by the special construction of the parts, as the twisters are rotated the series of wires are kept equidistant from each other, and when they are located above the bars *F* the bolt *h*, which projects from the bar *G*, will be located in the upper portion of the segmental slot *f*, and when reversed said bolt will be in the lower portion.

By connecting the frames to each other by an S-shaped link a dead-center will be avoided in the direction of the application of the power for rotating the frames.

I claim—

1. The combination, with the frame *D*, of a bar, *J*, a link connecting said bar to the frame, 75 arm *F*, secured to the frame, and arms *I*, secured to the bar *J*, and twisting devices pivoted on said arms *F* and *I*, substantially as set forth.

2. In a machine for the manufacture of combined wire and slat fences, the combination of a movable frame provided on one side with a series of inwardly-projecting arms, a bar attached to the frame by an S-shaped link and provided with a series of arms, *I*, bars *G*, and 85 twisting devices through which the wires pass pivotally connected to the arms *F* and *I*, substantially as shown, and for the purpose set forth.

3. The combination, with the movable frame 90 *D*, of the bar *J*, connected to the frame *D* by a link, arms *F*, connected to said frame *D*, twisting devices pivotally attached to said arms *F*, said twisting devices being provided with slots through which the wires to be twisted 95 pass, arms *I*, secured to the bar *J* and pivotally connected to the twisting devices, and an adjustable gage-block secured to said twisting devices, substantially as shown, and for the purpose set forth.

4. In a combined wire-and-slat-fence-making machine, a laterally movable frame provided with inwardly-projecting arms *F*, having ends with slots *f*, with which engage projecting bolts formed on bars *G*, said bars having slots *h*, an outwardly-projecting member, *G*', with cross-head *g*, having slots *g*', latches for retaining the wires within the slots *h*, arms *I*, pivotally attached to the opposite ends of the bars *G* and connected to a vertical bar, *J*, 105 which is attached by a link to the movable frame *D*, the parts being organized substantially as shown, and for the purpose set forth.

In testimony whereof I affix my signature in presence of two witnesses.

THEODORE F. VANDEGRIFT.
